FOREIGN PATENT DOCUMENTS

CA 506725 10/1954

Primary Examiner—Elizabeth A Albert*Assistant Examiner*—Karen E Eldridge Powers(74) *Attorney, Agent, or Firm*—Sheridan Ross P.C.(57) **CLAIM**

The ornamental design for a cap flap eyeglass modification, as shown and described.

DESCRIPTION

FIG. 1 is a perspective view of a cap flap eyeglass modification;

FIG. 2 is a left elevation view of the design illustrated in FIG. 1;

FIG. 3 is a top elevation view thereof;

FIG. 4 is a right elevation view thereof;

FIG. 5 is a bottom plan view thereof;

FIG. 6 is a rear view thereof; and,

FIG. 7 is another rear view thereof.

The broken lines showing a baseball-style cap in FIGS. 1–7 illustrate environmental matter and form no part of the claimed design.
